CLAIM

The ornamental design for a combined two part seat cushion, as shown and described.

DESCRIPTION

FIG. 1 is a front elevational view of a combined two part seat cushion showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The cross-hatching represents conventional fabric and is understood to extend throughout the areas represented.
